(57) **CLAIM**

The ornamental design for a food waste disposer, as shown and described.

DESCRIPTION

FIG. 1 is a front perspective view of a food waste disposer embodying our new design;

FIG. 2 is a rear perspective view of the food waste disposer of FIG. 1;

FIG. 3 is a front elevational view of the food waste disposer of FIG. 1;

FIG. 4 is a rear elevational view of the food waste disposer of FIG. 1;

FIG. 5 is a top plan view of the food waste disposer of FIG. 1;

FIG. 6 is a bottom plan view of the food waste disposer of FIG. 1; and,

FIG. 7 is a right elevational view of the food waste disposer of FIG. 1 with the left elevational view being a mirror image thereof.

In the drawings the broken lines are included to show portions of the food waste disposer that form no part of the claimed design.
